DESIGN FOR A FOOD MIXER

Clarence Karstadt, Glen Ellyn, Ill., assignor to
Birtman Electric Company, a corporation of
Illinois

Application June 1, 1948, Serial No. 146,709

Term of patent 14 years

(Cl. D44—1)

To all whom it may concern:

Be it known that I, Clarence Karstadt, a citizen of the United States, residing at Glen Ellyn, in the county of Du Page and State of Illinois, have invented a new, original, and ornamental Design for a Food Mixer, of which the following is a specification, reference being had to the accompanying drawings, forming a part thereof, in which:

Fig. 1 is a side elevational view of a food mixer, showing my new design; Fig. 2 is a front elevational view; Fig. 3 is a rear elevational view; Fig. 4 is a top plan view; Fig. 5 is a sectional view taken along line 5—5 of Fig. 1; and Fig. 6 is a sectional view taken along line 6—6 of Fig. 1.

I claim:

The ornamental design for a food mixer, as shown and described.

CLARENCE KARSTADT.
